UNITED STATES PATENT OFFICE.

JOSEPH WEBER, OF LIBERTY, NEW YORK, ASSIGNOR TO WILMOT L. MOREHOUSE, OF BROOKLYN, NEW YORK.

PERFORATING OR PUNCHING MACHINE.

969,737.

Specification of Letters Patent.

Patented Sept. 6, 1910.

Application filed August 10, 1909. Serial No. 512,170.

To all whom it may concern:

Be it known that I, JOSEPH WEBER, a citizen of the United States, residing at Liberty, in the county of Sullivan and State of New York, have invented certain new and useful Improvements in Perforating or Punching Machines; and I do hereby declare the following to be a full, clear, and exact description of the invention, such as will enable others skilled in the art to which is appertains to make and use the same.

My invention relates to improvements in perforating or punching machines designed to perforate paper, or other substances, in which an intermittent feeding device feeds the substance to be operated upon to the knife, or punch, in conjunction with the device for electrical contact to operate the punch, or knife, and a lever for lifting said knife, or punch, and the object of my invention is to provide a machine that will so feed the paper or other material to the punch, or knife, and its die that while locked the paper, or other substance, may be cut and the knife then thrown up, all at each revolution of the disk shaft, all for the purpose of making a perfect combination and for the purpose of cutting, or punching said paper, or other substance, with absolute certainty. I attain this object by the mechanism illustrated in the accompanying drawings in which—

Figure 1 is a side elevation of my perforating or punching device; Fig. 2 a front elevation taken on line *w* *w* of Fig. 1; Fig. 3 a perspective view of the knife-controlling device and Fig. 4 a diagram of circuits. Fig. 5 is a side elevation of a modification of my invention, and Fig. 6 is a second modification of the same.

Similar letters refer to similar parts throughout the several views.

In carrying out my invention, I provide a shaft D, which is equipped with disks A, B and R, the disk A having an upturned portion M formed therein by slitting the disk radially and upbending one wall of the slit. The disk B is provided with an insulation E¹ forming a certain portion of its surface adapted to open and close the circuit when such is formed, for a predetermined period during each revolution of the disk A for effecting engagement with a pin C carried by the disk R, the purpose of which

will presently appear. The shaft D is suitably driven by an electrical motor wired up to the usual batteries T and U, a toothed wheel N being engaged by the disk A, together with upturned portion or tooth M for its actuation, and is supported upon a shaft held in position upon the framework of the machine, said framework having a supporting base member B¹. The same shaft bearing the wheel N also carries the paper feeding rolls O and P, suitably journaled in said frame, and adapted to receive therebetween the paper Z of the paper roll Z¹, also suitably supported and journaled in position by adjunctive parts A¹ of the frame of the machine.

A shaft or rod B² is suitably upheld by a pivoted angular bracket B³, said shaft or rod being connected to an angular arm C² having adjustable connection with an additional angular arm C³, said latter arm being engaged by the pin or projection C carried by the disk R of the shaft D, and whereby said shaft or rod B² may be actuated when the parts are in electrical connection, as hereinafter disclosed.

Magnets V V are suitably supported in position upon a bracket F of the machine frame, and are arranged in electrical circuit by suitable wires G with the piano key mechanism D¹, the disk B and brush E being included in said circuit. A push rod Y is held in engagement with the armature W of the magnets V, by means of a spring H¹, said push rod having contact with the bar or rod J carrying the punch or cutter J¹, suspended above its die J², a stripper S being suitably interposed for the retention of the paper Z¹ passing between said punch and said die and suitably secured in position, as disclosed in Figs. 1 and 2.

The rod B² carries an arm K which is adapted for engagement with a lateral stud or projection K¹ of the push rod Y, and it will thus be noted that, as the rod B² is actuated as hereinbefore stated, said arm K will engage the projection or stud K¹ of the rod Y, and thus actuate the punch carried at the lower end of said rod. A spring L suitably held in place serves to hold the rod J in effective contact with the push rod Y, said spring having one end engaging said rod and its opposite end suitably anchored in fixed position.

It is evident that a cylinder may be used in place of the disk B with the brush E arranged to engage said cylinder laterally.

In the modification suggested by Fig. 5, I may employ a cylinder B-C and its brush in lieu of the disk B; also in lieu of the disk A may be employed a cylinder provided with mutilated or broken rings or rods A-C. It is noted that means for punching out new strips may be provided by operating the knife between electrical contacts at the punched portions of a strip after said strip has been once cut by the main machine. It is also noted that I may employ in connection with the shaft D a fly wheel F-W, while also a "kicking" rod 2 having applied thereto a headed screw 1 may be employed in connection with the armature 3 of magnets 4 and a spring 5 connected to said armature, included in an independent electrical circuit, for aiding the action of the plunger actuating rod J through the rocker shaft or rod B², the arm K and stud or projection K¹, as seen in Fig. 5, while as shown in Fig. 6 in connection with the above mentioned parts brushes 7 may be used which engage a cylinder 6 and a battery 8. The spring 5 is employed for effectively retracting the armature 3 when released from the magnets. In connection with the previously cut or perforated sheet or strip of paper Z, wound upon the roll Z², driven by a suitable motor as indicated in the upper left hand corner of Fig. 5, is employed a copper roll or cylinder D³, and a brush D², between which passes said strip or sheet of paper. The parts N¹, O¹, P¹, and A² perform the same functions in connection with the modified form of the device as disclosed by Fig. 5, as corresponding parts N, O, P and A of the preferred form of the machine, or that form disclosed in Fig. 1. The parts designated as D², and D³, with their adjunctive parts shown in connection therewith, are used in lieu of the piano key D¹ for aiding the feeding of the perforated or cut sheet of paper.

In operating the machine the shaft D is set in motion causing a feed of the paper or other substance under the knife J at each revolution of the shaft D and of the shaft of the roller O. Now upon the operator, at the key of a piano or other instrument, closing the circuit and charging the magnets V the armature W is brought down against the connecting rod Y which in turn hammers the punching rod J and punches the substance under the knife. In adjusting the movement of both the connecting and punching rods, it is advisable to limit the movement of the lower or punching rod J to a very small degree, and have the upper connecting or striking rod travel a greater distance so that when actuated it will strike a stronger blow than if it merely pressed or pushed against the lower rod or punch.

When the key is kept down constantly the amount of insulating and conducting surface on disk B is so arranged that the knife or punch J will punch out of the substance a hole of just the width of the punch making a continuous hole and that when the key is played intermittently or with the least tremolo there will always be a wall in the substance between each cut of the knife. After a length of paper or other substance has been punched, or perforated, according to the keys manipulated by the performer, it may be necessary to cause a duplicate copy to be made. Instead of the performer playing it over again, a series of contacts and a conducting roller suitably arranged in connection with the magnets may be employed so that the first or other copy when drawn between the conducting roll and contacts will operate the circuit instead of at a point of contact exterior to the machine itself, such as a piano key.

While I have been careful to show a perfect machine in all its details it is obvious that minor changes may be made and the principles maintained though mechanical equivalents may be substituted.

What I claim and desire to secure by Letters Patent is:

1. A punching or perforating machine, comprising a punch, means for feeding a strip of paper for engagement with said punch, a shaft, means for actuating said shaft, said shaft carrying a slotted disk with an upturned portion or tongue, means for intermittently actuating said shaft, a wheel engaged by said disk and adapted to actuate through said disk said paper-feeding means.
2. A device of the character described, including a punch, means for actuating said punch, means for feeding a strip or sheet of paper to said punch, means for intermittently actuating said shaft, a rocker shaft, means interposed between said shaft and the first referred to shaft, means carried by the first referred to shaft adapted to actuate the last referred to means, said punch having its carrying rod provided with a stud, said rocker shaft being provided with an arm engaging said stud.
3. A device of the character described, including a punch, a rod carrying said punch, a spring-controlled rod engaging the first referred to rod, a shaft, means for electrically actuating said shaft including magnets and an armature engaged by said magnets, said armature engaging the last referred to rod, and means for feeding a strip of paper under said punch.
4. A device of the character described, comprising a punch, a rod carrying said punch, a spring controlling said rod, an additional rod engaging the first referred to rod, a spring delivering upward pressure upon the second referred to rod, a shaft,

means for electrically actuating said shaft, means for feeding a strip of paper under said punch, including a wheel for actuating said paper feeding means and a disk carried by said shaft and engaging said wheel, said electrically actuating means for said shaft including magnets and an armature engaged by said second referred to rod.

5. A device of the character described, including a punch, means for carrying said punch, means for feeding a strip of paper under said punch, a shaft, means for electrically actuating said shaft, said shaft being provided with a disk, said disk being provided with an upstanding portion and a segmental insulator, said paper-feeding means including a wheel engaged by said disk, said shaft electrically actuating means including a brush engaging said disk, a

10 15 20

rocker shaft, having an arm engaging the punch-carrying rod, said disk carrying shaft being provided with a pin, and means interposed between and for actuating said rocker shaft by said pin.

6. A device of the character described, comprising a punch, a rod for carrying said punch, a shaft carrying a disk having an upturned projection, an additional disk having a segmental insulator and a third disk provided with a pin, means for electrically actuating said shaft, a rocker shaft, means for pivotally supporting said rocker shaft in position, said shaft carrying an arm adapted to engage a projection upon the punch-carrying rod, said means for electrically actuating said shaft including a piano key, circuit wires, magnets and an armature, and a push rod engaging the punch-carrying rod, said second referred to rod being engaged by said armature.

In testimony whereof I have signed my name to this specification in the presence of two subscribing witnesses.

JOSEPH WEBER.
